UNITED STATES PATENT OFFICE.

SELLMAR M. JACOBY, OF NEW YORK, N. Y.

DUST-COLLECTOR.

1,371,682.

Specification of Letters Patent. Patented Mar. 15, 1921.

Application filed September 11, 1917. Serial No. 190,747.

To all whom it may concern:

Be it known that I, SELLMAR M. JACOBY, a citizen of the United States, and resident of the borough of Manhattan, in the city 5 and State of New York, have invented a new and useful Improvement in Dust-Collectors, of which the following is a specification.

My invention relates to improvements in 10 collectors for dust and other light material bodies having novel means for collecting and assembling matter incident to the operation to which it may be applied.

One of the objects of this invention is to 15 provide a device which will by suction draw away from the work all foreign matter floating in the air and deposit the same in a chamber.

Another object is to provide a device having 20 a dust receiving chamber which may be readily cleaned of the matter collected therein without disturbing the machine with which it is operating.

Another object is to provide a device 25 which is portable and capable of a wide range of use.

Another object is to provide certain improvements in the form, construction and arrangement of the several parts whereby 30 the above and other named objects may be effectively carried out.

A practical embodiment of my invention is represented in the accompanying drawings in which,

35 Figure 1 represents a plan view of my improved collector.

Fig. 2 represents a side elevation of the same.

Fig. 3 represents a detail vertical section 40 taken in the plane of the line III—III of Fig. 2, looking in the direction of the arrows.

Fig. 4 represents a longitudinal vertical central section.

45 Fig. 5 represents a detail vertical section taken in the plane of the line V—V of Fig. 2, and

Fig. 6 represents an enlarged detail vertical section of one hinge member of the 50 hood, taken in the plane of the line VI—VI of Fig. 5.

The device herein shown and described for the purpose of illustration is intended and designed more particularly for use in 55 connection with fur beating machines, to be associated therewith for taking up and re-

moving the dust and other foreign matter from the articles being beaten, and is provided with a receiving chamber for the dust and foreign matter and exhausting air 60 therefrom and a means for producing a current of air through the same, which means is interposed between a hood for covering the work and the receiving chamber, but with little or no change in the essential parts 65 of the device it may be adapted to strain and purify the air for ventilation and other purposes.

The device comprises a main casing 1, open at opposite ends, a receiving chamber 70 2 secured to one of the open ends and a hood 3 arranged to cover the other open end and be swung away therefrom.

A suction fan 4 is mounted on a shaft 5 journaled in brackets 6, 7, in the casing 75 1, and is rotated by means of a belt 8 which connects a pulley 9 on the shaft 5 with a pulley 10 carried by the shaft 11 of a motor 12 secured to the top of the casing.

The receiving chamber 2 is formed with 80 two branches 13, 14, of which the horizontal branch 13 is directly connected to the casing and has a clean-out passage 15 which is closed by means of a cap 16. The cap 16 is removably held in position to close the 85 passage 15 by oppositely disposed hooks 17 on the cap which engage oppositely disposed pins 18 fast on the walls of the passage 15. The mouth of the passage is tightly sealed by means of a cupped washer 19 having a 90 disk of cloth or other similar material 20, which is arranged to be held against the walls of the passage by a spring 19*. While this disk of cloth seals the passage 15 it also serves to arrest the heavier dust or 95 foreign matter passing through the branch and collects it in a common mass, thus permitting it to be readily removed. The cap is also provided with a handle 16* by which it may be conveniently rotated to engage or 100 disengage the pins and hooks.

The vertical branch 14 is provided, near its upper end, with an annular channel 21, within which the dust of a lighter character may fall and be collected. Within the upper 105 open end of the branch 14, there is removably secured a conical strainer 22 of fine mesh wire, upon which is fitted a cover 23 of muslin, cheesecloth or other suitable material. The apex 24 of this strainer is pointed downwardly in a position directly over the passage 15, so that the dust which strikes the 110

cone will fall and be directed into the passage. The strainer is removably held in the opening of the branch 14 by means of hooks 25 on the strainer, which engage pins 26 on the branch 14, similar to the means employed for locking the cap 16 to the passage 15.

The strainer is also provided with a handle 27, by which it may be conveniently manipulated for purposes of removal.

10 The hood 3 is open along its bottom to receive the work and it is hinged to the casing 1 at the top by means of hooked bolts 28 which engage the reinforced rim 29 of the hood so that it may be swung toward and away from the work, as shown in dotted outline in Fig. 4. The hood is also provided with a window 30 arranged to slide in guides 31 formed in the front of the hood.

15 The casing having the receiving chamber and hood, is supported upon legs 32 which are locked to the casing by clamps 33 having bolts 34, thus permitting the device to be adjusted vertically on the legs.

20 In practice my improved dust collector is placed in position over a fur beating or other similar machine with the hood located over the table, as shown in dotted outline in Fig. 4, so that the motor driven fan will exhaust the air from the hood and create a suction 25 which will draw the dust and loose particles through the fan and casing into the receiving chamber, the lighter particles passing through the branch 13 and upwardly to the conical strainer which separates the dust 30 and air. The lighter particles which float upwardly and do not strike the strainer, will pass into the annular air chamber and rest there, while the heavier matter will fall from the strainer into the passage 15. The 35 air thus drawn into the receiving chamber readily passes through the muslin covering of the strainer to external atmosphere while the dust will be collected upon the surface of the fabric.

40 45 From time to time the strainer may be readily removed and the dust cleaned therefrom. The dust may be removed from the air channel through the opening for the strainer and the dust collected in the branch 50 13 taken out through the clean-out passage 15, by the removal of the cap 16.

55 It is obvious that various changes may be resorted to in the form, construction and arrangement of the several parts without departing from the spirit and scope of my invention; hence I do not intend to be limited to the details herein shown and described except as they may be specifically included in the claims.

60 What I claim is:

1. A dust collector comprising, a receiving chamber provided with vertical and horizontal branches, a strainer suspended from the top of the vertical branch, a clean-out passage in the horizontal branch in vertical alinement with the strainer, a hood, a tubular casing horizontally disposed between the horizontal branch and the hood, and a suction fan in said casing in open communication with the chamber and hood. 70

2. A dust collector comprising, a receiving chamber provided with vertical and horizontal branches, a removable strainer suspended from the top of the vertical branch, a clean-out passage in the horizontal branch in vertical alinement with the strainer, a hood, a tubular casing horizontally disposed between the horizontal branch and the hood, and a suction fan in said casing in open communication with the chamber and hood. 75

2. A dust collector comprising, a receiving chamber provided with vertical and horizontal branches, a removable strainer suspended from the top of the vertical branch, a clean-out passage in the horizontal branch in vertical alinement with the strainer, a hood, a tubular casing horizontally disposed between the horizontal branch and the hood, and a suction fan in said casing in open communication with the chamber and hood. 80

3. A dust collector comprising, a receiving chamber provided with vertical and horizontal branches, a conical strainer suspended from the top of the vertical branch, a clean-out passage in the horizontal branch in vertical alinement with the strainer, a hood, a tubular casing horizontally disposed between the horizontal branch and the hood, and a suction fan in said casing in open communication with the chamber and hood. 85

4. A dust collector comprising, a receiving chamber provided with vertical and horizontal branches, a removable conical strainer suspended from the top of the vertical branch, a clean-out passage in the horizontal branch in vertical alinement with the strainer, a hood, a tubular casing horizontally disposed between the horizontal branch and the hood, and a suction fan in said casing in open communication with the chamber and hood. 90

5. A dust collector comprising, a receiving chamber provided with vertical and horizontal branches, a removable conical strainer suspended from the top of the vertical branch, a clean-out passage in the horizontal branch in vertical alinement with the strainer, a cap for said passage, means for locking said cap to the passage, a hood, a tubular casing horizontally disposed between the horizontal branch and the hood, and a suction fan in said casing in open communication with the chamber and hood. 95

6. A dust collector comprising, a receiving chamber provided with vertical and horizontal branches, a removable conical strainer suspended from the top of the vertical branch, a clean-out passage in the horizontal branch in vertical alinement with the strainer, a spring-pressed cap for said passage, means for locking said cap to the passage, a hood, a tubular casing horizontally disposed between the horizontal branch and the hood, and a suction fan in said casing in open communication with the chamber and hood. 100

7. A dust collector comprising, a receiving chamber provided with vertical and horizontal branches, a removable conical

strainer suspended from the top of the vertical branch, a clean-out passage in the horizontal branch in vertical alinement with the strainer, a spring-pressed cap having a disk 5 of cloth interposed between said cap and passage, means for locking said cap to the passage, a hood, a tubular casing horizontally disposed between the horizontal branch and the hood, and a suction fan in said casing in open communication with the chamber and hood.

10 8. A dust collector comprising, a receiving chamber provided with vertical and horizontal branches, said vertical branch

having a laterally extending annular air 15 channel near its top, a removable conical strainer suspended from the top of the vertical branch, a clean-out passage in the horizontal branch in vertical alinement with the strainer, a hood, a tubular casing horizontally disposed between the horizontal branch and the hood, and a suction fan in said casing in open communication with the chamber and hood.

20 In testimony that I claim the foregoing 25 as my invention, I have signed my name this 4th day of September, 1917.

SELLMAR M. JACOBY.
